UNITED STATES PATENT OFFICE.

EDWIN C. HENN, OF CLEVELAND, OHIO, ASSIGNOR TO THE NATIONAL-ACME MANUFACTURING COMPANY, OF CLEVELAND, OHIO, A CORPORATION OF OHIO.

SELF-OPENING DIE.

No. 895,636.

Specification of Letters Patent. Patented Aug. 11, 1908.

Application filed July 1, 1905. Serial No. 267,968.

To all whom it may concern:

Be it known that I, EDWIN C. HENN, a citizen of the United States, residing in Cleveland, in the county of Cuyahoga and State of Ohio, have invented certain new and useful Improvements in Self-Opening Dies, of which the following is a specification.

This invention has reference to devices for cutting threads on rods or other stock in machine tools, especially of the class known as turret lathes or automatic machine tools, wherein at the proper stage, the device is closed and advanced relative to the stock to form the thread, and thereupon automatically the cutting members in the device swing out away from the threaded stock, so that there is no necessity for reversing either the stock or the die to remove the tool from the threaded stock.

20 One of the objects of the invention is to provide means for automatically and positively moving the holders or jaws in the device, both to and from, their operative position.

25 Another object of the invention is to provide a form of tool holder or jaw by which standard stock die segments or chasers can be securely and adjustably mounted in the holders, and particularly the stock button dies.

30 Another object of the invention is to provide means for properly adjusting such chasers to and from the cutting line after they have been secured in the holder.

35 A further object of the invention is to provide a means for operating the chaser jaws that is independent of the movement of the die in the tool carrier or of the movement of such carrier.

40 In the drawings accompanying and forming a part of this specification showing one embodiment of my invention, Figure 1 is a perspective view of the device, one of the holders being removed. Fig. 2 shows the adjusting plate. Fig. 3 shows the clamping screw. Fig. 4 shows one tool holder removed. Fig. 5 shows a die-segment or chaser. Fig. 6 shows a holder having a chaser formed integral therewith. Fig. 7 shows in plan the cam member and the cooperating portions of the tool holders. Fig. 8 shows the device partly in elevation, and partly in longitudinal section. Fig. 9 is a section of the cam member on line a—a of Fig. 8. Fig. 10 is a vertical section of a por-

tion of the machine showing the means for operating the die and its jaws. Fig. 11 is a front elevation. Fig. 12 a side elevation of the parts shown in Fig. 10. Fig. 13 is an elevation enlarged from the opposite side; 60 and Fig. 14 is a fragmentary view similar to Fig. 10 but enlarged.

In the embodiment of my invention shown in the drawings, on a shank 15, is suitably secured a head 16; which members may have 65 an axial bore 17, to accommodate the stock, if desired. To the head 16 are pivoted a plurality of tool holders or jaws, two being shown in the present instance, but obviously a greater number might be provided; all of 70 which are mounted on pivots to swing toward and from the axis of the head. Each of the tool holders is shown as comprising a block 18, from which projects an arm 19, having an aperture 20. On opposite sides 75 the head is provided with a slot 21, extending radially, in which snugly fits the apertured arm 19, pivoted therein by means of a pin 22, passing through an aperture 23, in the head and through the aperture 20, in the 80 said arm. The block 18, has a slot extending from one end to the other thereby forming side members 24, that are preferably under-cut, forming a dove-tailed slot. In such slotted portion of the block is snugly fitted a 85 plate or slide 25, having its side walls correspondingly tapered to engage the under-cut side member.

In order to suitably clamp a chaser or die segment 14 of the usual semi-circular form as 90 shown in Fig. 5, the block 25, is provided with semi-circular recess 26 in its face at one end, of approximately the same outline as the chaser 14, but of less depth than the thickness of the chaser. A clamping plate 95 27, has an elongated central opening 28, larger than the shank of a bolt 29, that screws into a threaded hole 30, in the block 25. By this means the plate 27, can be clamped on the block 25, in a number of 100 positions and secure the chaser in the recessed portion. The plate 27 has at one end a pair of opposite lugs 31, that extend from the upper end of the plate, and by their inner faces engage the end portions of the diametral face of the chaser. At its opposite end, the plate 27 has a lug 32, projecting into a slotted end portion 33, of the block; the latter lug being provided with a threaded aperture in which screws an adjusting bolt 110

34, that engages the end of the block and causes the other lugs 31, to tightly clamp the chaser in its recess. It is found expedient to have the recess of such depth that the chaser will project a short distance beyond the face of the block and engage the inner face of the clamping plate. At the other end of the plate such face is provided on each side with a projection 35, corresponding in height to the distance the chaser projects beyond the block. By this means the clamping plate is offset from the block, and the screw 29 will cause the plate to tightly clamp the chaser in the recessed part of the block. The chaser having been thus secured in the recess the slideable block 25, is adjusted toward the cutting line by means of screws 36, located in threaded apertures in a cross-piece 37, secured to the block at one end. When adjusted in proper position, the slide is clamped in this slot by means of screws 38, in one side of the holder that engage one of the sliding faces of the block; which may be grooved if desired as shown at 39 in Fig. 6. While means are shown for clamping a substantially semi-circular chaser, it is obvious that other forms can be secured to the block 25, by suitably altering the shape of the recess therein correspondingly. If desired, the chaser and sliding block 25, may be made integral, such as the member 40 shown in Fig. 6, in which case the clamping plate 27 is dispensed with.

For the simultaneous opening and closing of the die-holders, is provided a double cam member 41 that rocks on the shank 15, adjacent to the head. The cam member has oppositely extending cam arms 42, somewhat hook shaped. On each said holder is suitably secured a bar 43, having at its extremity a roller 44, arranged to engage with the inner eccentric face 421 of one of the cam arms 42. This engaging face of the cam is eccentric, and the swinging of the cam member will thereby cause the cam arms to rock the die holders on their pivot pin 22, moving them away from the stock. To return the die holders to their operative position, a bolt 45, screwed into a threaded aperture in the extremity of each arm 19, is arranged to engage a cam face 46, on the cam member, there being two such cams, diametrically opposite on the member, for simultaneous engagement with the bolts 45. By this means, the swinging of the cam member in one direction will cause its arms 42, engaging the rollers 44, to thereby move the die segments outward. And the swinging of the cam member in the opposite direction, by the engagement of the bolts 45, with the cam faces 46, will cause the die segments to swing inward to their operating position. It will be noticed that the cams 42, have a gradual curvature, whereby a slow outward movement is given to the holders; while the cam faces 46, are comparatively abrupt, serving to swing the holders quickly to their operative position. And the bolts 45, thereupon engage a concentric face 47, on the cam member, serving to retain the holders in their operative position. By the adjustment of these bolts 45, the wear on them and their co-operating faces is compensated for, so that the die segments can be accurately adjusted to cut the proper depth of thread. Additional means are also provided for limiting the movement of the holders to the operative position, comprising a pair of screws 48, tapped into the end of the head, that form abutments for the adjacent faces of the heads. These bolts are locked in position by means of set screws 49, in the head.

In Figs. 10 to 14 are shown one form of means for operating the cam member of the device, applied to a screw lathe. On the bed 50 of the machine is mounted a tool carrier 51, slideable in ways 52, toward and from the stock carrier, not shown. The shank 15 of the die holder is supported in an aperture in the carrier 51, and has a limited sliding movement therein, being held normally in the position shown in Fig. 11 by a coil spring 53 on the shank, that permits the die to advance a short distance toward the stock, which is the usual construction in such devices, so that the die can follow the thread faster than it is being fed, if necessary. A slide 54 is movable in a guide 55 secured to the frame 50. The upper end of the slide is bent transversely, and carries a rod 56 extending parallel with the shank 15. This rod 56 is arranged to extend between the arms of the forked extremity of an arm 57 extending radially from the cam member 41. In the position of these parts as shown in Fig. 10, the slide is in its lowermost position, and the die is closed. The slide is prevented from moving downward from such position by a stop pin 58 that engages the end of the guide 55. If the slide is moved upward from this position the bar 56 will rock the forked arm 57 and thereby cause the jaws of the die to open. And upon being returned to its former position the slide will move the bar 56 to again rock the cam member and close the jaws. Since the bar 56 projects through the forked arm in a direction parallel with the path of movement of the carrier 51 supporting the die member, it will be seen that the die member can move through a considerable range without affecting its control by the bar 56 and slide; and the position of the die segments relative to their supporting head is independent of any longitudinal movement of the carrier. The segments will be opened or closed by the proper movement of the slide, irrespective of the position of the carrier within its range of longitudinal movement.

Suitable means are provided for reciprocating the slide 54 at the proper stage in the

operation of the machine. In the drawings the slide is shown as pivoted to a lever 59 that is fulcrumed on a bar 60 secured to the frame 50. A pin 61 is secured to the lower 5 end of the slide 54 and is arranged to be engaged by a roller 62, mounted on a drum 63 that is rotated from the main shaft of the machine by any suitable means, not shown. On the free extremity of the lever 59 is 10 mounted a bolt 64, which portion of the lever is preferably bent as indicated in Fig. 14, to incline the bolt to extend radially of the drum 63. A second roller 65 is also mounted on the drum 63, and at the proper stage engages 15 the bolt 64, and rocks the lever 59, advancing the slide 54. These rollers 62 and 65 are so arranged relatively on the drum 63, that at the proper stage, the roller 65 moves the engaged bolt 64 and operates the lever 20 and slide to move the jaws from their normal open position to the closed position. Thereupon the die and stock are relatively advanced, and the stock rotated to cut the thread; as soon as the thread is cut, the pin 25 61 is engaged by the roller 62 to move the slide 54 upward and quickly open the die, releasing it from the threaded stock. It will be observed that this opening movement of the die segments is independent of any longitudinal movement of the die, and is positively accomplished as soon as the thread is 30 cut, thereby obviating any necessity of retracting relatively the die and stock. This construction will also overcome the disadvantages 35 of spring movements generally used to retract the die segments or jaws. At the same time the die has a limited movement on the carrier controlled by the spring 53, so that the die can follow the thread if necessary. 40 But this latter movement will not effect in any way the opening of the die jaws by the slide and forked arm of the cam, since the latter operate precisely the same notwithstanding this movement of the die.

45 Having thus described my invention what I claim is:

1. In a die, the combination of a head, a plurality of jaws pivoted on the head, means for securing a die-segment on each jaw, comprising a block having a recess at one end portion that has one wall arranged to engage one side of the segment and which recess has a wall shaped to engage one edge of the segment, a plate engaging the other side of the segment and having projecting arms engaging the edge of the segment adjacent its ends, said plate having a lug on its other end containing a threaded aperture, a bolt in such aperture in the lug engaging the block to force said pair of arms into engagement with the segment, and means for forcing the plate and block together to clamp the segment therebetween.
2. In a machine tool, the combination of a tool carrier, a die member mounted on the

carrier, die-segments movably carried on the die member to open and close, a guide member fixed on the frame of the machine, a slide movable in the guide member, a driving shaft, means actuated from said shaft for reciprocating said slide, and means for effecting the movement of the die segments in both directions by said slide.

3. In a machine tool, the combination of a tool carrier a die member mounted on the carrier, die-segments on the die member movable to open and close, a member movable on the die member to operate the die-segments in both directions, a slide arranged to engage the latter operating member, a guide fixed on the frame of the machine in which said slide reciprocates, a driving shaft, a rotary member driven from said shaft, and a pair of projections on said rotary member arranged to alternately connect with said slide to reciprocate it and thereby effect the opening and closing of the die segments.

4. In a machine tool, the combination of a tool carrier movable on the frame to and from the stock carrier, a die member mounted on the carrier, die segments movably carried on the die member, a controlling member arranged to operate the die segments to open and close, a fork projecting from the controlling member, a guide fixed on the frame of the machine, a slide arranged to reciprocate in the guide, an arm fixed to the slide and extending parallel with the path of movement of the tool carrier and located in said fork, a driving shaft, a drum rotated from said shaft, and a pair of projections on the drum arranged to alternately connect with and operate said slide, whereby the die-segments are positively operated irrespective of the position of the carrier and die member throughout its range of operative movement.

5. In a machine tool, the combination of a tool carrier movable on the frame to and from the stock carrier, a die member mounted on the carrier, die-segments movably carried on the die member, a controlling member arranged to operate the die-segments to open and close, a fork projecting from the controlling member, a guide fixed on the frame of the machine, a slide arranged to reciprocate in the guide, an arm fixed to the slide and extending parallel with the path of movement of the tool carrier and located in said fork, a lever fulcrumed on the frame and pivoted to the slide, a driving shaft, a drum rotated from said shaft, and a pair of projections on the drum arranged to alternately connect with and operate said lever, whereby the die segments are positively operated irrespective of the position of the die member throughout its range of operative movement.

6. The combination of a driving shaft, a carrier supported for longitudinal movement, a head thereon, a plurality of swinging die carrying jaws on said head, means swinging

in a plane transverse to the plane of movement of the carrier and operatively connected to said jaws to move them, and means comprising a rod slidably connected with said swinging means and located at one side of and in parallelism with the plane of movement of the die carrier and operated by said shaft for opening and closing the jaws whatever be the longitudinal position of said carrier.

7. The combination of a cam shaft, a carrier supported for longitudinal movement, a head thereon, a plurality of swinging die-carrying jaws on said head, means swinging in a plane transverse to the plane of movement of said carrier and operatively connected with said jaws to positively open and close them, and means supported free of said movable carrier and operated by said shaft and operatively connected with said swinging means for operating it to open and close the jaws.

8. The combination of a cam shaft, a carrier supported for longitudinal movement, a head thereon, a plurality of swinging die-carrying jaws on said head, a cam for opening and closing said jaws and supported to swing in a plane transverse to the plane of movement of the carrier, means supported free of the carrier and operated by said shaft and operatively connected with said swinging cam for positively opening and closing the jaws.

9. The combination of a driving shaft, a carrier supported for longitudinal movement, a head thereon, a plurality of swinging die-carrying jaws on said head, and means oper-

ated by said shaft for opening and closing said jaws and comprising a slide having a member extending lengthwise of the head, a support for said slide, and means operatively connecting said slide with said jaws and comprising a member movable on said lengthwise extending member.

10. The combination of a shaft, a carrier supported for longitudinal movement, a head thereon, a plurality of swinging die-carrying jaws on said head, swinging means supported for movement in a plane transverse to the plane of movement of the carrier and operatively connected with said jaws, and means in constant engagement with said swinging means and also movable in a plane transverse to the plane of movement of the carrier and fixed against movement in the direction of movement of said carrier and operated from said shaft for operating said swinging means to positively open and close the jaws whatever be the longitudinal position of the carrier.

11. In a machine of the class specified; the combination of a head having a plurality of swinging die carrying jaws, each having a dovetailed recess, a die carrying block movably supported therein, a clamping plate for securing said die carrying block in position, means for clamping the plate and block together, and means for adjusting the die carrying block in its dovetailed recess.

EDWIN C. HENN.
